UNITED STATES PATENT OFFICE

EDMUND C. SCHWEITZER AND NICKOLAS J. CONRAD, OF CHICAGO, ILLINOIS, ASSIGNEES
TO SCHWEITZER & CONRAD, OF CHICAGO, ILLINOIS, A CORPORATION OF ILLINOIS.

LIGHTNING-ARRESTER.

1,302,229.

Specification of Letters Patent. Patented Apr. 29, 1919.

Application filed October 18, 1917. Serial No. 197,172.

To all whom it may concern:

Be it known that we, EDMUND C. SCHWEITZER and NICKOLAS J. CONRAD, citizens of the United States, residing at Chicago, in the county of Cook and State of Illinois, respectively, have invented a certain new and useful Improvement in Lightning-Arresters, of which the following is a full, clear, concise, and exact description, reference being had to the accompanying drawings, forming a part of this specification.

Our invention relates to lightning arresters for electrical apparatus.

15 Many different forms of disturbances on electrical circuits are classed as "lightning". The common characteristic of all such disturbances is an abnormal increase in potential. This may occur from various causes and in various ways, that is, either a steady increase in potential or variable or oscillatory depending upon the cause. There are in the usual distributing systems so many causes beside atmospheric electricity which 20 may contribute to the creation of abnormal conditions of potential that the term lightning is somewhat of a misnomer.

The ideal protection against disturbances would be secured by protective devices 25 which would eliminate the causes of such disturbances. Practically, however, it is impossible to guard against the various types of disturbances individually and they operate so irregularly and in such an unforeseeable manner that the apparatus employed at present is designed to relieve the disturbance with as little commotion or damage as possible.

It has been common heretofore to provide 30 a few arresters of large capacity upon the lines to be protected on the assumption that a disturbance must be wholly relieved by each individual arrester for the district over which it is supposed to be operative. Because of the large capacity required such arresters are necessarily expensive. The result has been that generally a line has been 35 insufficiently protected. The majority of disturbances are not of primary magnitude and could be relieved by an arrester of relatively small capacity, but the large capacity is needed in that form of protection to handle the discharges of a greater magnitude.

As approaching closely to the ideal condition of protection, we provide arresters of

limited capacity and of relatively inexpensive construction at or about the point of connection of each piece of apparatus to the line. If a disturbance of magnitude greater than can be relieved by one arrester occurs 30 the other arresters on the line, adjacent help to allay the disturbance. Thus, for instance, in the usual distributing system, we place an arrester at each transformer. We 35 possibly limit the discharge capacity of each arrester so that in the event of a breakdown only small damage or disturbance can be produced by operation of that arrester.

Our invention provides a multi-gap arrester of a novel form having individual 70 blowout means for each gap. The invention further provides an improved structure for the individual gap and provides a device of marked simplicity and reliability and low cost. Another feature of improvement is 75 the unit construction to facilitate manufacture in assembling of the device. Other objects and advantages of our invention will be apparent from the following detailed description of an illustrative embodiment of 80 our invention.

We do not intend to be limited to the details of the particular embodiment hereafter described, the scope of our invention being set out in the appended claims.

In the accompanying drawings which form a part of the present specification—

Figure 1 is a longitudinal axial cross-sectional view of one form of our invention;

Fig. 2 is a bottom plan view of the same;

Fig. 3 is a transverse cross-sectional view taken on the line 3—3 of Fig. 1;

Fig. 3^A is a perspective view of one of the blocks;

Fig. 4 is a fragmentary longitudinal section of a device employing a modified form of block;

Fig. 5 is a transverse cross-sectional view of the structure shown in Fig. 4;

Fig. 6 is a longitudinal axial cross-section 100 of a different embodiment of our invention.

Fig. 7 is a section taken on the line 7—7 of Fig. 6; and

Fig. 8 is an isometric detail view of one 105 of the electrodes.

The arrester shown in Figs. 1 and 2 comprises a cylindrical casing or shell 1, preferably made of porcelain. This cylindrical shell is supported in a porcelain bracket 2, to which it is secured at by glazing in the 110.

manufacture of these parts. A sheet metal terminal disk 3 having a depressed central portion adapted to fit within the inner bore of the tube 1 closes the upper end of said tube. The upper end of the tube 1 is cut away, as shown at 4 to permit introduction of the wire 5, which is connected to line. A spring terminal socket 6, which is adapted to make contact with one end of the resistance element 7 is fastened as by means of the rivet 8 to the head or disk 3 with the bare end of the wire 5 clamped between these parts. The head 3 and the upper end of the tube 1 are covered by a cap member 10 which cap member is cemented upon the end of the tube. To aid the cement in securing a firm hold, grooves 11 are formed on the cap and tube members. It will be noted that the terminal wire 5 enters a groove below the edge of the cap 10 and passes through the walls of the tube 1 at a point within the cap 10. This provides protection against the entry of moisture.

The resistance member 7 may be constructed of any suitable material, such resistance elements being now obtainable on the market. The metallic caps 12 and 13 upon the ends of the resistance rod 7 form terminals coöperating with suitable socket terminals 6 and 14 respectively. The socket terminal 14, which is similar to the terminal 6, is connected to and mounted upon an electrode member 15 which projects into the upper one of a series of blocks 17. The block 17 may be made of any suitable insulating material, such as lava, porcelain, asbestos, or any suitable molded compound, the chief desideratum being that the blocks 17 shall be able to withstand the heat created by the lightning discharge without excessive damage. The blocks 17 are cubical in configuration and are of a size such that they will just nicely fit within the bore of the tube 1, as is shown in Fig. 3. In one face of each cubical block 17 there is formed a cavity 18 either molded in or formed as by means of drilling. The cavity is extended beyond the center of the cube to form a small air compartment 19 back of the electrodes 20 and 21, which project into each cavity 18. Metallic electrode members 22 in the form of small elongated cylinders having collars at the center extend from one side of a cavity 18 in one block to the other side of a cavity in the other block, so that the opposite ends 20 and 21 form terminals in adjacent openings in the block 17. The collar formed on the electrode member at its center prevent movement to the electrode member with respect to the adjacent blocks. The collar preferably rests in a counter-sunk opening in the adjacent faces of the block, to permit the blocks to have their adjacent faces in contact, although this is not necessary. The blocks 17 may be arranged as

shown in Fig. 1 with their openings 18 all facing in the same direction or the openings may be staggered to increase the arc over a distance between them.

The lower end of the tube 1 is closed by a plug 24 having a rim 25 adapted to engage the corners of the lowermost block 17 for supporting the spark gap unit in proper relation. The lowermost electrode member 26 is riveted to the terminal wire 27. This terminal wire passes out through an opening in the plug 24. The plug 24 is provided with another opening 28 which may be plugged or left open as desired. The wire 27 is connected to ground. The openings where the wires 5 and 27 enter the device are sealed with suitable compound.

The operation of the device above described is as follows:

When an undue potential exists on the line the space between the electrodes 20 and 21 is broken down and sparks or arcs are formed at the gaps between said electrodes. These electrodes are formed of non-arcing metal which is well known in the art, tending to suppress the arcs after they are formed. We do not depend solely upon the non-arcing character of the metal as we have provided blow-out means for each gap. The chamber 19 back of the electrodes 20-21 contain air, which upon the initiation of a spark at the corresponding gap, is heated up suddenly and as it expands it blows outward through the gap, thus tending to extinguish the arc. The resistance rod 7 limits the rate of discharge and limits the flow of current in case of unforeseen failure of the gaps 20-21.

In Figs. 4 and 5 we have illustrated a modified form of the device employing cylindrical blocks having flat side faces 31. Each block has a cavity 18 as described in connection with the blocks 17 and the double ended electrode members 22 are employed to form spark gaps in the cavities as previously described. The blocks 30 have holes 32 arranged on opposite sides on the ends and pins 33 are set in these holes to keep the blocks in alignment. The blocks are set with the openings 18 facing alternately in opposite directions. This arrangement of the openings provides a maximum arc over distance between openings.

The operation of this form is substantially the same as described in connection with Figs. 1, 2 and 3. With the blocks 30 a resistance rod 7 is included in the same manner as shown in Fig. 1.

In Figs. 6, 7 and 8 we have illustrated a modified form of our invention. In this structure a plurality of paths having multiple gaps in series is provided. A main block member 35 has radial rows of recesses 36 formed in the lower face thereof. These holes are preferably formed by drilling.

Radial slots are then cut in the web between the holes 36—36 of a depth sufficient to receive the shank 37 of the double ended electrode members 38.

5 The electrode members 38 are provided with heads 39 at each end, each head being formed with an arcuate face 40. These electrode members 38 are placed within the slots and the heads are formed so as to fit 10 within the adjacent walls of the openings 36 and lie substantially flush with the surface of the block 35. At the center a compound electrode member 41 is provided, this being composed of a central circular member 42 having electrode heads 43 similar to the heads 39 of the electrode members 38 formed integral therewith and extending in the line of the grooves previously described. The outermost electrode members 43' project 15 out and are electrically connected to a band or circular joining piece 44 having ears 45 extending upwardly under the screws 46. The wire 47 which forms a terminal connected to ground is connected on its inner 20 end to said band or connecting member 44. The members 41, 38 and 43 are stamped out of non-arcing sheet metal. A cover plate member 48 having rows of openings 49 registering with the openings 36 is secured over 25 the lower face of the block 35 to hold the electrode members in position and to form continuations of the chambers 36. A central screw bolt 50 is connected to the central electrode 30 41 and is connected at its outer end to a cup shaped terminal 51. The cover plate 35 48 is fastened to the block 35 by screws placed in the quarters between the rows of holes 36—49. A casing or shell 52 surrounds the block 35 and the cover plate 48 and has 40 a conical portion 53 extending downward. At its lower end the conical portion 53 supports a terminal clip or socket 54 connected to the wire 55 which runs to line. Between the terminals 51 and 55 is connected the 45 resistance rod 56, which is similar to the rod 7 as shown in Fig. 1. The upper part of the block 35 and the casing 52 is covered by a cap member 57 which is secured in place by means of the screws 46 and 58.

50 Suitable supporting ears or lugs 59 are connected to the casing 52 and provide suitable means for supporting the device on a cross-arm or on the wall or the like. In the lower end of the conical member 53 a plug of 55 insulation 60 closes the end of the casing and supports the socket 54. The wire 55 enters through the plug 60. The ground wire 47 enters the casing by means of a plug of insulation 63. The openings through 60 these plugs and about the wires 47—55 may be sealed by compound, as may also the other parts of the device.

Instead of employing separate blocks 35 and 48, the electrode members may be molded in place. The casing 52—53 may be

made of metal and in that event the wire 47 may be attached either to the lugs 59 or directly to the casing 52—53, as desired.

It is to be noted that in this form the chamber 36 which lies back of the spark gap 70 has communication with the outside openings 49 to a more restricted space than in the form shown in Figs. 1 and 4. It is to be understood, however, that the holes 48 in the forms shown in Figs. 1 and 4 as well as in 75 the forms shown in Figs. 6 to 8 may be of other configuration than circular. The degree of restriction may also be varied.

In all the forms illustrated the proximity of the inclosing walls tend to cool and hence 80 extinguish the arcs independently of the blow-out effect.

We do not intend to be limited to the use of the novel form of spark gap structure in series with a resistance as the same may be 85 employed in any situation found desirable. We contemplate the use of the spark gaps for general protective purposes.

While the device is preferably supported in vertical position, as shown in Fig. 1, we 90 contemplate placing the arresters shown in Figs. 1 to 5 in a horizontal position so that if either end of the casing breaks off the wire and the corresponding end will drop down and open the circuit still farther. 95

We do not intend to be limited to the details of construction shown and described.

We claim:

1. In a protective device, a block having an open recess therein, said recess having a 100 chamber back of the pins, and cylindrical pins projecting through the sides of the block into said recess, said pins having shoulders of larger diameter than the pins, said shoulders being set in recesses in the 105 sides of the block, said shoulders serving to space the ends of the pins apart to form a fixed spark gap.

2. In a protective device, a pair of blocks having flat end faces, a lateral recess in each 110 block, a common electrode member projecting through the adjacent end face of each block into the chambers and other electrode members projecting into the recesses in the blocks to form spark gaps with the common 115 electrode member.

3. In a protective device, a pair of blocks having engaging end faces, a lateral recess in each block, a common electrode member projecting through the end faces of each 120 block into the recesses and other electrode members projecting into the recesses in the block to form spark gaps with the common electrode member, said common electrode member having integral means for preventing displacement with respect to both of 125 said blocks.

4. In a protective device, a pair of blocks having adjacent end faces, a lateral recess in each block, a common electrode member 130

- projecting through the end face of each block into the recess therein, other electrode members projecting into the recesses in the blocks to form spark gaps with the common electrode member, and means for holding the blocks against rotary displacement.
5. In combination, a plurality of double ended metallic electrode members and insulating means supporting said members end to end with spark gaps between them, said insulating means providing chambers back of said spark gap and outlets in front of said spark gap, said electrode members having lateral projections to space the electrodes accurately with respect to said chambers and each other.
6. In combination, a plurality of double ended metallic electrode members and insulating means supporting said members end to end with spark gaps between them, said insulating means providing chambers back of said spark gap and outlets in front of said spark gap, said electrode members having enlarged portions preventing endwise movement of the same in the insulating means.
7. In a protective device, a tubular sleeve of insulation, a metallic plate having centering means projecting into the bore of the tube for centering the plate in one end of the tube, a socket terminal member connected to said plate, a resistance rod within the sleeve engaging the socket, a cap member for the sleeve and a terminal wire passing into the sleeve under the cap and connecting with said terminal member.
8. In a protective device, a tubular sleeve of insulation, a metallic plate having centering means projecting into the bore of the tube at one end thereof, a socket terminal member connected to said plate, a resistance rod within the sleeve engaging the socket, a plurality of spark gaps connected in series with the resistance rod, a cap member for the sleeve, and a terminal wire passing into the sleeve under the cap and connecting with said terminal member.
9. In combination, a sleeve of insulation, a socket terminal in one end of the sleeve, a closure for said end, a resistance rod having one end engaging said socket, a block fitting into the tube, a lateral recess in said blocks, said blocks having an electrode member projecting through the end of the blocks into said recess, said electrode member having a shoulder resting upon the block and a terminal socket for the adjacent end of the resistance rod secured to said electrode.
- 50 10. In combination, a sleeve of insulation, a socket terminal in one end of the sleeve, a closure for said end, a resistance rod having one end adjacent said socket, a plurality of blocks fitting into the tube, lateral recesses in said blocks, the blocks adjacent the other end of the rod having an electrode member 55 projecting through the end of the block into the corresponding recess, said electrode member having a shoulder resting upon the block, a terminal socket for the adjacent end of the resistance rod secured to said electrode, other electrode members projecting into the recesses of adjacent blocks to form 60 spark gaps, and an electrode member projecting into the recess of the remote block, said latter electrode member being connected 65 to a terminal wire and having a shoulder for engaging the adjacent blocks.
- 70 11. In combination, a pair of prismatic blocks having lateral recesses extending beyond the axis of the blocks, axial bores being 75 formed through said blocks, a double ended cylindrical pin forming an electrode projecting through said bores into said recesses, said electrode having an enlargement at the center thereof, one of the blocks having a 80 counter-bore on the side facing the other block, adapted to receive the enlargement on the electrode.
- 85 In witness whereof, we hereunto subscribe our names this 13th day of October, A. D. 90 1917.

EDMUND O. SCHWEITZER.
NICHOLAS J. CONRAD.
